UNITED STATES PATENT OFFICE.

JAMES RIGBY, OF PATERSON, NEW JERSEY, ASSIGNOR OF ONE-HALF TO
WILLIAM HOLT, OF PATERSON, NEW JERSEY.

LOOM.

No. 349,168.

Specification of Letters Patent.

Patented April 2, 1907.

Application filed May 19, 1906. Serial No. 817,664.

To all whom it may concern:

Be it known that I, JAMES RIGBY, a citizen of the United States, residing in Paterson, county of Passaic, State of New Jersey, have invented certain new and useful Improvements in Looms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention relates to looms, and it has in view to so construct a loom, particularly with respect to its shuttle-actuating means, as to make it adapted not only to the weaving of several webs or widths of goods at a time, but to the weaving of different widths.

Other objects are to simplify and cheapen the construction with relation to its possible output and render it more durable, better adapted for general wear and tear, and more mechanically perfect in various respects than looms at present in common use having the pivoted picker-stick as the essential element of the shuttle-actuating means.

These objects and others of more or less importance I accomplish with the loom shown by way of illustration in the accompanying drawings, wherein—

Figure 1 is a view in side elevation of my improved loom. Fig. 2 is a view in front elevation of said loom, certain parts being broken away. Fig. 3 is a view in plan on a larger scale of the batten and other parts carried by and adjoining the same. Fig. 4 is a vertical sectional view of the batten, taken just to the left of one of the pickers, Fig. 2. Fig. 5 is a detail view illustrating the picker construction, and Fig. 6 illustrates certain parts of my invention as adapted to a box-loom, the view being in plan.

In said drawings, *a* is the loom-frame; *b*, the breast-beam; *c*, the lay-swords carrying the batten *d* of special construction, as herein-after described; *e*, the cam-shaft journaled in the frame *a* and carrying cams *f* and *g*; *h*, the crank-shaft, also journaled in the frame *a* and connected in the usual manner with the lay-swords by the pitmen *i*; *j*, the harness, and *k* the controller-lever, all said parts, excepting

the batten, being arranged and constructed substantially the same as in ordinary looms. At suitable distances in the back wall *l* of the batten *d* are arranged reeds *m*. These may be of any width or of different widths, if desired, according to the respective widths of the several pieces or webs which the loom is to weave. The batten is formed with a vertical slot *n*, which may, if desired, be co-extensive with substantially the whole length of the batten and which is covered by a top or race plate *o*, secured on the top of the batten by screws *p* or otherwise and having slots *q* coinciding with the slot *n* and arranged each between two weaving-spaces.

The section of the back wall *l* of the batten immediately back of each slot *q* is formed with a slit *r*, in which plays a swell *s*, forming the back wall of a shuttle-box whose front wall is formed by the usual strip *t*, adjustably secured on the top or race plate *o*. Each swell is provided on its back with two clips *u*, which receive the upper ends of fingers *v*, carried by a rock-shaft *w*, which is fulcrumed in brackets *x*, secured to the back of the batten, there being one such rock-shaft for each two fingers. Each shaft carries a dagger *y*, which projects forwardly under the batten and is adapted to engage or miss engaging a longitudinally-movable knock-off bar *z*, sliding in brackets *l* on the breast-beam according as the presence or absence of a shuttle in the corresponding shuttle-box effects or fails to effect the movement of the wall or swell *s* of the shuttle-box. Bar *z* is normally pulled to the right by a spring *2*, connecting it with the breast-beam. When a notch *3* in said bar is engaged with a stop *4*, the spring is under tension, and upon the bar being disengaged from said stop by one of the daggers *y* it effects the shifting of the controller in a manner and by means well known in the art and unnecessary to particularly describe and show herein, and stops the loom. 5 designates plate-springs carried by the brackets *1* and acting to press the bar *z* against the stop *4*.

There will of course be as many shuttles as there are webs or pieces of goods to be woven. It is contemplated that the shuttles move back and forth on the lay or batten together, each with respect to its particular web, and that each of the shuttle-boxes (except the

end ones) shall serve for two adjoining shuttles, one entering and leaving it from one side and the other entering and leaving it from the other side. I therefore provide 5 the following mechanism for actuating the shuttles.

On the batten over the slots *n* are arranged to slide pickers *6*, each composed, preferably, of laminae of leather riveted together, as best 10 shown in Fig. 5, and formed with a narrow vertical opening *7*. Depending from the batten is a series of brackets *8*, carrying rollers *9*, on which runs the upper bar *10* of a sliding frame comprising said bar, a parallel bar 15 *11*, and plates *12*, which hold said bars in fixed relation to each other. By this arrangement bar *10* is braced throughout its entire length, so that it is prevented from losing shape, and so running untrue on the rollers. 20 In bar *10* at suitable intervals corresponding to the distances between shuttle-boxes are series of vertical narrow openings *13*.

14 designates one of the spring picking-fingers, (see Fig. 5,) each consisting of a wire 25 bent in its middle portion to form a sort of loop *15* and having its extremities bent in opposite directions, as at *16*. One of these picking-fingers is mounted in the bar *10* in the manner shown in Fig. 5, where its loop 30 projects upwardly through one of the openings of the series of openings *13*, while its extremities *16* lie flat against the under side of the bar and are there held by clips *17*, surrounding the same and the bar. Each finger 35 is removable from the bar by simply slipping the clips lengthwise of the bar until the extremities *16* are cleared.

The sliding frame is reciprocated from the cams *f* by means of levers *18*, fulcrumed at 19 40 in the loom-frame, and flexible connections *20*, passing over pulleys *21*, journaled in brackets *22*, carried by the batten.

23 are levers actuated from the cams *g* for controlling the shedding mechanism. (Not 45 shown.)

Fig. 6 shows my invention as adapted to a box-loom, 24 being a cellular shuttle-box movable vertically in the usual manner and by the employment of well-known means in 50 a recess *25* cut in the back of the batten, 26 entrance-guides for the shuttle, and 27, 28, and 29 being respectively the sliding frame, picking-finger, and picker constructed and arranged substantially the same as the corresponding parts already described, except that they operate with reference to the back 55 of the batten instead of with reference to its under side, where they would be in the way of the vertically-moving shuttle-box.

60 The operation of my improved loom will be apparent from the foregoing description, the reciprocations of the picking-fingers with the sliding frame causing the pickers to

alternately throw one and then the other of the two shuttles which are controlled by each 65 of said picking-fingers except the end ones.

It will be observed that the action of the pickers on the shuttles and of the picking-fingers on the pickers is at all times a straight thrust, so that friction is not only eliminated, 70 but the danger of throwing a shuttle off the lay reduced to the minimum. Again, the form of the picking-fingers, whereby they have considerable elasticity, contributes considerably to impart to the shuttles just that 75 motion which is necessary in a properly-working loom in order to avoid undue vibration and lay the filler nicely in the shed.

It will be apparent that by comparatively inconsiderable changes my improved loom 80 may be adapted to the weaving of various widths of goods, if desired, no two being alike.

Having thus fully described my invention, what I claim as new, and desire to secure by 85 Letters Patent, is—

1. In a loom, the combination of the batten, and a shuttle-actuating means comprising a series of spring picking-fingers, pickers arranged on said picking-fingers, and a 90 support for said picking-fingers movable parallel with the batten, substantially as described.

2. In a loom, the combination of the batten, and a shuttle-actuating means comprising 95 a sliding bar extending parallel with the batten and movable longitudinally, spring picking-fingers detachably secured to said bar, and pickers arranged on said fingers, substantially as described.

3. In a loom, the combination of the batten and a shuttle-actuating means comprising a sliding bar extending parallel with the batten and movable longitudinally, wire picking-fingers having loop-shaped portions extending 100 upwardly from said bar, and pickers arranged on the loop-shaped portions of said fingers, substantially as described.

4. In a loom, the combination of the batten having a vertical slot extending approximately from one end thereof to the other, pickers, devices for actuating said pickers engaged therewith and projecting through said slot, and a plate having aligned slots receiving said devices, said plate being 115 removably secured on the top of the batten whereby to be interchangeable with another or other plates having slots of different lengths, substantially as described.

In testimony that I claim the foregoing I have hereunto set my hand this 14th day of May, 1906.

JAMES RIGBY.
